FLYER SPINNING MEANS

Albert Nau-Touron, Le Vesinet, France, assignor
to Isaac Frenkel, Paris, FranceApplication July 6, 1939, Serial No. 282,991
In France July 25, 1938

14 Claims. (Cl. 57—67)

The present invention has for its object a process and means for passing the yarn for rotary spinning and twisting members. Said process and said means which are utilisable in a general manner and in particular on frames for spinning and twisting natural and artificial textiles, can also be used for cabling or a similar operation.

The invention consists, in its main principle, in causing the yarn to pass, before it winds on the rotary spooling or similar member, in such a manner that it is applied at least once on said member or on the yarn or thread already wound on the latter.

Practically, the application of the yarn is effected on a zone opposed to that on which the winding occurs.

In a form of construction utilising a spinning flyer of the type described and illustrated in the French Patent No. 684,493 dated February 7, 1929, in the name of the applicant, said spinning flyer has perforations or the like arranged in such a manner that the yarn after it frictionally passes on the outer wall of the spinning flyer and before winding on the rotary spooling member, passes on the yarn already wound, with a certain amount of pressure, according to a convex line and then passes through the wall of the spinning flyer and finally winds on said member.

The invention can be applied, not only to devices of the type comprising a spinning flyer, but also to systems having the same functions and in particular:

(a) To flyers the ends of which comprise, in this case, blades each provided with two perforations for the passage of the yarn as previously indicated;

(b) To rotary ring travellers;

(c) To fixed ring travellers;

(d) To bowls, bells or similar members.

The perforations for the passage of the yarn in the spinning flyer, flyers or the like can laterally open through a groove, slot or the like which is judiciously inclined for introducing or extracting the yarn, said perforations being located in one and the same plane or in different planes suitably spaced apart.

The rotary spooling member, such as a spindle or the like effecting on said member or on its bobbin the spooling action, can be a driving member, the mentioned flyer or the like effecting the twisting and the relative drag in angular speed for the spooling and exerting the tension on the yarn being simply braked.

Reversely, the flyer or the like effecting the twisting of the yarn can be a driving member,

the spooling member such as a spindle or the like effecting the spooling and exerting a tension on the yarn being simply braked.

In the latter arrangement contemplated, it is possible to obtain, under correct conditions either in function of the diameter which is variable of the spooling, the braking of the spooling member by the action of the yarn passing on the wound part.

The control of the mentioned flyer or the like can be applied to the prior systems.

The invention also relates to an embodiment in which the parts of the flyer, traveller, bowl, bell or the like, through which the yarn passes are made of metal resistant to wear, for instance, of steel, the other parts being made of light metal or light metal alloy.

In a modification, not only the parts through which the yarn passes, but also the zones on which the yarn bears are made of metal resistant to wear.

The parts made of hard metal are preferably encased upon casting in the light metal.

The invention also includes other particular points which will appear in the following text given with reference to the accompanying drawings, by way of example only, in which:

Fig. 1 is a general elevation of a first embodiment of a controlled bobbin according to the invention.

Fig. 2 is a plan view corresponding to the preceding figure.

Fig. 3 is a general elevation of a second embodiment according to the invention in the case of a controlled spinning flyer.

Fig. 4 is a corresponding plan view.

Fig. 5 is a general elevation of an embodiment applied to a flyer.

Fig. 6 is a corresponding plan view.

Figs. 7 and 8 are details of the blades terminating the flyers.

Fig. 9 is a diagrammatic elevation of a traveler devised for carrying out the process.

Fig. 10 is a corresponding plan view.

Figs. 11, 12 and 13 illustrate various embodiments of flyer devices.

Fig. 14 is a view showing the bobbin with its braking system.

Fig. 15 is a corresponding plan view of said braking system.

Fig. 16 corresponds to Fig. 1 but shows a constructional modification.

Fig. 17 corresponds to Fig. 3 but shows another modification.

Fig. 18 is a section, on an enlarged scale made according to line XVIII—XVIII of Fig. 16.

In the embodiment more particularly illustrated in Figs. 1 and 2, the yarn 1, the balloon strand of which is indicated at 1^a, engages in a spinning flyer 2 through the perforation 3 opening laterally for allowing the said yarn to be placed in position or removed. It then passes, on a certain length and according to a certain arc, 10 on the outer peripheral part of said spinning flyer 2 and engages in a perforation 4 opening laterally. It then passes against the part of the yarn already wound on the bobbin 5 and subsequently passes through the wall of the spinning flyer 15 through a perforation 6 which opens laterally. The yarn finally returns towards the bobbin and winds on the latter by again passing through the wall of the spinning flyer through a perforation 7 which can also open laterally. 20 In the example illustrated, the bobbin 5 which is a driving bobbin, rotates to the left in the direction of the arrow f¹ (general case of twisting), the spinning flyer being braked by any suitable means and in particular by a yarn-drag 2^a. The 25 yarn 1 follows the circuit indicated by the successive arrows f², f³, f⁴, f⁵ and f⁶. A peripheral friction of the yarn 1 is thus obtained on the layers of yarn already wound on the bobbin 5. This friction assists the yarn in its function for 30 driving the spinning flyer and the parts and members which are rigid therewith. Owing to this passage of the yarn, the narrow and therefore difficult passage of the spooling points 8 is rendered easier, so that it is possible to spin (or twist) finer yarns or to manufacture yarns of less twist. 35

The location of the various peripheral holes 3, 4, 6 and 7 is suitably devised to function for the purpose to be attained. The holes 4 and 6 which 40 determine the plane of mutual friction of the yarn, are arranged, in the example of Figs. 1 and 2, in a plane at right angles to the spindle.

Moreover, the hole 7 is located in this plane. The holes 4 and 6 can be located in a plane 45 which is oblique relatively to the spindle, the hole 7 being arranged so that the spooling takes place, either in a zone located at a level higher or lower than that of the friction zone of the yarn, or at the same level as said friction zone. 50 This system allows, by a judicious choice of the spooling level, of facilitating passing the point 8 and the neighbouring zone.

The passage of the yarn according to the invention prevents the vibrations of the bobbin 55 and of the spindle owing to the opposite and balanced actions of the radial and opposed resultants generated by the tension of the yarn. Furthermore, a mutual smoothing of the yarn is obtained as it frictionally passes on the layers all 60 ready wound.

For introducing the yarn 1 in the spinning flyer, use can be made, not only of the hole 3, but also of any one of the holes 3^a, 3^b etc., so as to modify the value of the angle according to which 65 the yarn embraces the spinning flyer.

This conditioning of the tension of the yarn between the balloon strand 1^a and the tangent winding strand 1^b is effected before the yarn passes through the hole 4.

70 For the rotation of the bobbin 5 in the direction reverse to that indicated by the arrow f¹ and thus in the general case of spinning, the passage of the yarn would be the same as that previously indicated, but the holes 3^b, 3, 3^a, 4, 6 and 7 would be arranged, relatively to the posi- 75

tion indicated in Fig. 2, with respect to the positions illustrated, symmetrically to the axis x y.

The spinning flyer 2 might also be reversed, its upper ridge 9 being then placed at the lower part. The passage of the yarns is identical and the holes and slots are arranged, as previously indicated in function of the direction of rotation of the spindle. As set forth hereinafter, this arrangement of the reversed spinning flyer can allow an appreciable reduction of the bore of the 10 latter.

In the example illustrated in Figs. 3 and 4, the driven member is the spinning flyer 2, the same members as those of Figs. 1 and 2 being designated by the same reference numerals in said 15 Figs. 3 and 4.

The spinning flyer rotating, for instance to the right, according to the direction of the arrow f¹ (general case of spinning), the yarn 1 (balloon strand 1^a) successively engages in the holes 3, 4, 20 6 and 7. The same advantages are obtained as those previously indicated. However, in the first embodiment, the braking action must be exerted on the spinning flyer whereas in this second embodiment, it must be exerted on the bobbin 5. 25 Now, this braking of the bobbin is automatically obtained by the yarn frictionally passing on the wound layers. Moreover, said friction action is variable according to the very variations of the spooling diameter of the bobbin. Said variable braking can be sufficient, but it can be completed by a constant braking action.

The same particular remarks and arrangements indicated concerning Figs. 1 and 2 also apply to said second embodiment. 30

Figs. 5 to 8 illustrate an improved flyer devised according to the invention in view of obtaining the particular passage of the yarn 1.

The yarn 1, after partially winding on the branch 10 of the flyer, passes through the hole 40 11 formed in a blade 12 and then engages in the holes 4^k of the blade 12 and the holes 6^k and 7^k of a blade 14 terminating the other branch of the flyer. Said holes 4^k, 6^k and 7^k substantially correspond to the position of the holes 4, 6 and 45 7 of the two first embodiments and the same advantages indicated concerning the latter are obtained with the improved flyer which can also be reversed.

A bracelet 50, made of metal or alloy and of 50 suitable cross section, circular or not, is rigid with travellers 3¹, 3¹_a, etc. or the like, suitably arranged on the bracelet 50. Said travellers are preferably rigid with the ring 51 so as to be stationary with the latter, said ring which is fixed 55 in the form illustrated, having any suitable cross section. The yarn 1 (balloon strand 1^a) coming from the drawing or doffing cylinders, engages, according to the method above set forth, in any one of the travellers 3¹, 3¹_a or 3¹_b and preferably 60 winds on the bracelet 50. After having passed through the traveller 3¹, the yarn 1 rubs on the bobbin 5, successively engages in the travellers 6¹, 7¹ and finally winds on the bobbin 5 which is a driving bobbin in the example illustrated. 65

The passage of the yarn 1 corresponds to a spinning operation, that is to say to a rotation of the bobbin 5 in the direction of the arrow f¹, while the ring 51 and bracelet 50 are stationary.

In an alternative form of the invention, the 70 ring 51 and the bracelet 50 can be driven, the bobbin being braked.

Figs. 11 to 15 illustrate an embodiment in which a bar 21 is secured to the frame of a spinning device 22 by means of arms 23. A ring 24, 75

mounted on balls or the like can freely rotate relatively to the bar 21. Said ring 24 carries an annual member or spinning flyer 2. Through the medium of a rope or the like 26, the ring 24 and consequently the spinning flyer 2 can be 5 rotatively driven. The spindle 5 rotates and pivots on its pivotal rod 30 which is secured to the bed 31 having a reciprocating movement defined by the arrows 32. The spindle 5 spooling 10 the yarn comprises a groove 33 and a drum 34. In the groove 33 acts a braking element 35 secured at one end whereas the other end receives a dragging weight 36. Use can be made of rocking or sliding members 36a or any other suitable 15 braking means (mechanical, electric, or the like).

Uprights 37 guide the beds 31.

The yarn 1, coming from the drawing or feeding system 39 passes on yarn-guide 40 and in a 20 fixed or vertically movable ring 41.

The ring 41 can be replaced by two threads 42 (Figs. 12 and 13). The ring 41 and the two 25 threads 42 can moreover be done away with.

The ring 24 and its spinning flyer 2 can be devised for ensuring the passage of the bobbin, a 30 brake allowing to stop the ring carrying the spinning flyer during the operation of the spinning frame.

The drum 34 serves to wind up a few under 35 turns of the yarn which saves time upon the lifting operation and eliminates the readjusting operation.

The formation of the bobbins can be effected, either in parallel layers (Fig. 14) or in conical 40 layers as shown in different phases in Figs. 11, 35 12 and 13, or in any other manner.

The yarn coming from the yarn-guide 40, passes through the ring 41 or between the threads 42 and engages in one of the peripheral holes 3 of the spinning flyer 2. Said yarn externally 45 rubs on the spinning flyer, passes in the hole 4 of the spinning flyer 2 and directly winds on the spindle or, according to the arrangement indicated concerning Figs. 1 to 8, which arrangement is particularly applied to Fig. 11.

An arrangement reverse to that illustrated in 50 Figs. 11 and 12 can be used for the spinning flyer 2. Said reversed arrangement is shown in Fig. 13 in which the spinning flyer 2 is reversed. The 55 passage of the yarn is consequently reversed, the yarn passing through the bore of the ring 24 and of the spinning flyer 2 with all the necessary freedom and it issues externally through the hole 4 then through the chosen peripheral hole 3. This arrangement allows of reducing the bore of 60 the ring 24 and of the spinning flyer 2 and of obtaining thereby greater speeds and certain constructional facilities.

Instead of controlling the bobbin, the ring 24 and consequently the spinning flyer 2 can be 65 controlled.

The control of the driving members can be effected individually, in groups, or together and it is either mechanical (ropes, spindle cords, belts or the like), or electric.

It is obvious that the embodiments described 70 and illustrated are given herein only by way of indication and not in a limiting sense. All modifications or changes which do not alter in any way the main features above set forth or the desired result, remain included in the scope of the present invention.

What I claim as my invention and desire to 75 secure by Letters Patent is:

1. In a device for passing the yarn for rotary spinning and twisting members applicable in

particular to frames for spinning and twisting natural and artificial textiles and for cabling or similar operation, in which use is made of a spinning flyer which is provided with perforations so arranged as to be effective to cause the yarn after 5 frictionally passing on the outer wall of the spinning flyer and before being wound on the rotary spooling member, to pass on the yarn already wound with a certain pressure, and means on said flyer causing the yarn to wind thus along 10 according to a convex line and then pass through some of said perforations, the wall of the spinning flyer and finally wind on said member.

2. A device as claimed in claim 1 wherein the 15 perforations provided in the spinning flyer can laterally open for the introduction or the extraction of the yarn, and said perforations are located in predetermined positions and spaced apart.

3. A device as claimed in claim 1 wherein the 20 rotary spooling member such as a spindle or the like, effecting on the same or on its bobbin the spooling action, can be a driving member, the spinning flyer or the like effecting the twisting and the relative drag in angular speed for the 25 spooling and exerting the tension on the yarn being simply braked.

4. In a device for spinning and twisting textiles of the kind provided with a spindle for a filling bobbin and a movable member coaxial with said spindle and revolving in the same direction as the latter, said movable member and spindle undergoing relative axial displacements for distributing the thread on the filling bobbin, the combination of a rotary member provided with rigid thread-passing guides so distributed thereon as to cause 30 the thread received from the delivery members after frictionally passing about said rotary member along a line connecting two distinct points of the rotary member to extend into the interior of the latter, then bear on a layer of thread already 35 wound on the bobbin, and again traverse one of the rigid guides of the rotary member and is thereafter disposed on the latter along a second line connecting two distinct points on said rotary member, and so forth, in order finally to be 40 wound on the bobbin.

5. In a device for spinning and twisting textiles of the kind provided with a spindle for a filling bobbin and a movable member coaxial with 45 said spindle and revolving in the same direction as the latter, said movable member and spindle undergoing relative axial displacements for distributing the thread on the filling bobbin, the combination of a ring constituting a rotary member for guiding passing thread and having guiding apertures distributed on the circumference of 50 said ring in such manner as to cause the thread received from the delivering members to pass into a first aperture and then pass frictionally about the surface of the ring, and extend into a second aperture at a distance from the first, then bear on a layer of thread already wound on the 55 bobbin, thereafter pass into a third aperture of the ring, to bear on the surface of the latter, pass into a fourth aperture of said ring at a distance from the third and finally be wound up on the bobbin.

6. In a device for spinning and twisting textiles of the kind provided with a spindle for a filling bobbin and a movable member coaxial 70 with said spindle and revolving in the same direction as the latter, said movable member and spindle undergoing relative axial displacements for distributing the thread on the filling bobbin, the combination of a ring constituting a rotary 75

member, provided with means acting as a brake on the rotation of said ring, and rigid guides distributed on said ring in such manner thereon as to cause thread drawn from the delivering members to be frictionally disposed about said rotary member along a line connecting two distinct points of the rotary member and extend into the interior of the latter and bear on a layer of thread already wound on the bobbin, and again 10 traverse a rigid guide of the rotary member again to be frictionally disposed about the latter along a second line connecting two distinct points and so forth, in order finally to be wound on the bobbin.

13. 7. In a device for spinning and twisting textiles of the kind provided with a spindle for a filling bobbin and a movable member coaxial with said spindle and revolving in the same direction as the latter, said movable member and spindle 20 undergoing relative axial displacements for distributing the thread on the filling bobbin, the combination of a ring constituting a rotary member provided with thread passing and guiding apertures distributed on the circumference of said ring in such manner thereon as to cause the thread received from the delivering members to pass into a first aperture and after being frictionally disposed about the surface of the ring a second aperture at a distance from the first and bear on a layer of thread already wound on the bobbin, then enter a third aperture of the ring, and after again being frictionally disposed about the surface of the latter to enter a fourth aperture at a distance from the third and finally 30 be wound on the bobbin, and means conditioned to act as a brake on the rotation of said ring.

8. A device according to claim 4, wherein a plurality of rigid guides are distributed on the rotary member so that the lines of contact between 40 the thread and said rotary member can be determined at will, according to the thread, in length and angular position on the rotary member in such manner that the transverse components applied on the bobbin carrying spindle 45 tend to balance each other and eliminate vibrations.

9. In a device for spinning and twisting textiles of the kind provided with a spindle for a filling bobbin and a movable member coaxial with said spindle and revolving in the same direction as the latter, said movable member and spindle 50 undergoing relative axial displacements for distributing the thread on the filling bobbin, the combination of a ring constituting a rotary member and provided with thread passing and guiding apertures distributed in such manner thereon as to cause the thread received from the delivering members to enter a first aperture and after being frictionally disposed about the surface 55 of the ring, to enter a second aperture removed from the first in the direction of the rotation of the end to bear on a layer of thread already wound on the bobbin, then enter a third aperture which is spaced less than 180° from either 60 of the two first apertures and then after again being frictionally disposed against the exterior of the ring, to enter a fourth aperture removed from the first in the direction of the rotation of the ring a distance which is less than 180° from either of the first two apertures and then finally 65 to be wound on the bobbin.

10. In a device for spinning and twisting textiles of the kind provided with a spindle for a filling bobbin and a movable member coaxial with 70 said spindle and revolving in the same direction

as the latter, said movable member and spindle undergoing relative axial displacements for distributing the thread on the filling bobbin, the combination of a ring constituting a rotary member provided with means conditioned to act 5 as a brake on the rotation and with thread passing and guiding apertures distributed in such manner thereon as to cause the thread received from the delivering members to enter a first aperture and after being frictionally disposed about 10 the surface of the ring to enter a second aperture spaced away from the first in the direction of the rotation of the ring, then to bear on a layer of thread already wound on the bobbin, and enter a third aperture which is spaced less 15 than 180° from either one of the two first apertures and then after again being frictionally disposed upon the exterior of the ring to enter a fourth aperture spaced away from the first in the direction of the rotation of the ring a distance 20 less than 180° from either of the first two apertures, and finally to be wound on the bobbin.

11. In a device for spinning and twisting textiles, the combination of a filling bobbin carrying spindle, means for axially guiding said spindle and simultaneously allowing the same to rotate, means for braking the rotation of said spindle, means imparting alternating axial displacements to said spindle, a ring adapted for rotation coaxially with said spindle, means for moving said ring in continuous rotation, and rigid guides for the thread distributed on said ring in such manner as to cause the thread received from the distributing members to become engaged between the spindle and the ring and traverse a guide of said ring, and after being frictionally disposed on the external surface of said ring, to engage with a second guide, then engage upon a layer of thread wound on the bobbin, again traverse a third guide of said ring and after again being 30 frictionally disposed on the external surface of the ring, to engage with a fourth guide upon the ring and finally to be wound on the bobbin.

12. In a device for spinning and twisting textiles of the kind provided with a spindle for a filling bobbin and a movable member coaxial with said spindle and revolving in the same direction as the latter, said movable member and spindle undergoing relative axial displacements for distributing the thread on the filling bobbin, the 45 combination of a rotary member provided with rigid thread passing guides distributed in such manner thereon as to cause the thread received from the delivering members to pass into a first 50 guide of the rotary member, then into a second guide situated at a lower level on said member by rubbing on the outer surface of said member along a line which is oblique with respect to the axis, thereafter to extend into the interior of the rotary member after bearing on a layer of 55 thread already wound on the bobbin, and traverse a third guide, and again bear with friction on the exterior of the rotary member and to pass into a fourth guide on the latter in order to be 60 finally wound on the bobbin.

13. In a device for spinning and twisting textiles of the kind provided with a spindle for a filling bobbin and a movable member coaxial with said spindle and revolving in the same direction as the latter, said movable member and spindle undergoing relative axial displacements for distributing the thread on the filling bobbin, the combination of a rotary member provided with rigid thread passing guides distributed in such 70 manner thereon as to cause the thread received 75

from the delivering members to pass into a first guide of said rotary member, enter a second guide of the latter situated at a lower level thereon by rubbing on the exterior surface of said member along a line that is oblique with respect to the axis, and extend into the interior of the rotary member while bearing on the layers of thread already wound on the bobbin, and then traverse a third guide situated at a higher level than the second, again to bear with friction on the exterior surface of the rotary member and thereafter enter a fourth guide in order finally to be wound on the bobbin.

14. In a device for spinning and twisting textiles of the kind provided with a spindle for a filling bobbin and a movable member coaxial with said spindle and revolving in the same direction as the latter, said movable member and spindle undergoing relative axial displacements

for distributing the thread on the filling bobbin, the combination of a rotating member provided with rigid thread passing guides distributed thereon in such manner as to cause the thread received from the delivering members to pass 5 into a first guide on the rotary member, then into a second guide situated at a lower level thereon and while rubbing on the exterior surface of said member along a line that is oblique with respect to the axis, to extend into the interior of the rotary member after bearing on a layer of the thread already wound on the bobbin, traverse a third guide, again be disposed with friction on the exterior surface of the rotary member, and thereafter to traverse a fourth 10 15 guide situated at a level higher on said rotary member than the third guide, in order finally to be wound on the bobbin.

ALBERT NAU-TOURON.
